CARBURETOR

Edward A. Winfield, La Canada, Calif.

Application June 26, 1928. Serial No. 288,399

14 Claims. (Cl. 261—41)

The present invention has to do generally with carburetors and particularly with a type of carburetor having such characteristics that changes in operating conditions are automatically compensated.

The general object of the invention is the provision of a carburetor of such nature that an internal combustion engine equipped therewith may be operated with maximum speed, power, 10 acceleration and economy. To this end I have provided the device with means whereby it compensates automatically for variations in operating temperature or altitude without being of complicated construction or necessitating the 15 use of moving parts. It is commonly known that moving parts in a carburetor are sources of trouble and generally cannot be kept in adjustment for a satisfactory length of time. Furthermore, a complicated carburetor usually cannot be successfully adjusted to operate most efficiently, 20 except at the factory, as it is beyond the ability of the average mechanic to make such adjustment. The present carburetor not only permits economical, flexible and smooth operation of the motor, 25 but it accomplishes these ends without sacrificing maximum power and speed.

An additional important feature of the invention is that certain parts may be inverted so the carburetor may operate either as a down draft 30 or an upward draft type. The operation of the carburetor as a down draft type is particularly satisfactory in that no "loading" or collecting of gasoline particles occurs in the intake manifold (preferably of a down draft type in this instance) 35 of the engine, as the flow of combustible mixture from the carburetor is aided rather than retarded by the force of gravity, which retarding tendency exists in the upward draft type. With the aid of gravity, less suction is required to maintain uniform flow of fuel, and this, in turn, makes it possible to reduce the inlet air velocities in the 40 intake manifold and carburetor passages. By virtue of these conditions, the intake passageways can be increased in size without sacrificing proper slow speed performance of the engine. Larger intake passageways serve to increase the 45 volumetric efficiency of the motor which by virtue of its consequently increased efficiency, develops 50 more power, especially at high speed.

The manner in which the above and additional features of the invention are accomplished will be most readily and clearly understood from the following detailed description and the annexed 55 drawings, in which:

Figs. 1 and 2 are plan and side elevation views, respectively, of the carburetor;

Fig. 3 is a sectional view on line 3—3 of Fig. 1, the spray tube and parts within the wells being shown in elevation;

60

Fig. 4 shows a broken away portion of Fig. 3, the spray tubes being shown in section and the throttle valve being shown in changed position;

65

Fig. 5 is another, fragmentary view of Fig. 3 illustrating the valve in another position;

65

Fig. 6 is an enlarged, fragmentary section on line 6—6 of Fig. 3;

65

Fig. 7 is an enlarged fragmentary section on line 7—7 of Fig. 3;

70

Fig. 8 is an enlarged, fragmentary section on line 8—8 of Fig. 3;

70

Figs. 9 and 10 are detached views of the throttle or valve device;

75

Fig. 11 is a view generally similar to Fig. 5 but with the throttle valve removed;

75

Fig. 12 is a section on line 12—12 of Fig. 1;

75

Fig. 13 is a fragmentary section on line 13—13 of Fig. 1;

75

Fig. 14 is a fragmentary section on line 14—14 of Fig. 1;

80

Fig. 15 illustrates a variational type of carburetor body construction to permit the adjustment of certain parts to inverted position;

80

Fig. 16 is a section on line 16—16 of Fig. 15; and

85

Fig. 17 is a fragmentary section on line 17—17 of Fig. 3.

85

Referring to the drawings, numeral 20 indicates a carburetor body which is seen to define a float bowl, generally indicated at 21, an air inlet 22, a combustible mixture outlet 23, and a valve or carbureting chamber 24. As will later be seen the body may be formed sectionally to enable adjustment of the carbureting chamber to inverted position from that shown in Fig. 3, but for present purposes of description the body may be considered as having unitary construction, and the position of the carbureting chamber in relation to the float bowl fixed as shown in Fig. 3. The float bowl embodies a liquid inlet 25, a screened passage 26 leading from the inlet to the bowl interior, and a needle valve 27 for regulating the flow of liquid from passage 26 into the bowl. A float or liquid level control 28, pivotally mounted to the body at 28a, and pivotally joined to the valve at 28b, serves to adjust the valve vertically in accordance with the liquid level in the bowl.

90

Atmospheric access to the interior of the bowl is gained through passageway 29. Since the structural nature of the float bowl is in no way con- 100

100

105

110

trolling on one phase of the present invention and since the bowl may be of any suitable standard type, the disclosed bowl, in view of this one phase may be considered merely as typical.

Inlet 22 and outlet 23 are of circular cross section and are seen to converge slightly toward valve chamber 24, which chamber is of cylindrical formation, the common axis A-B of the inlet and outlet intersecting axis C of the valve chamber at substantially right angles. Rotatively mounted in chamber 24 is a cylindrical throttle or valve plug 30 having at each end trunnions 31 and 31c journaled in bearings 30a and 30b, respectively, the former bearing being fitted into the body at 31a and the latter into cover 80 (see Fig. 17). The cover is removably held on the body by screws 80, which may be taken out when it is desired to remove the cover from the body and the valve plug from its chamber. Extending diametrically through the valve plug is a passage 32 of cylindrical formation and adapted to register with the inlet and outlet passageways when the plug is in the full open position of Fig. 5. As will later be made apparent in a description of the carburetor operation, passageway 32 may be considered a mixing or carbureting chamber. Slots 34 and 35 are formed in the valve as indicated in the drawings, these slots extending from the outer surface of the valve into passage 32 and serving purposes which will hereinafter be described. The valve has formed on one of its ends a shoulder 36, (Figs. 9, 10 and 12) the purpose of this shoulder being to limit the movement of the valve in the direction indicated by the arrow D (see Figs. 3 and 12) through engagement with the end of adjustable screw 38, releasably positioned by lock nut 38a and mounted in the carburetor body, and in an opposite direction through engagement with a body rib 37 extending between the journal boss 33 and the body 20. Clamped to trunnion 31 is an arm 39 to which suitable attachment may be made for effecting and controlling the movement of the valve. Thus it is seen that body rib 37 serves as a fixed stop to limit the rotation of the valve at wide open position, and screw 38 embodies an adjustable stop to regulate the extent of opening of the valve in its idling position.

Within bores 40 and 41 in the carburetor body and offset from the air inlet 22, is a pair of reservoirs or wells generally indicated at 42 and 43, these wells being termed respectively, the intermediate speed well and the high speed well; the reason for which terminology will later appear. It is a feature of particular advantage that the wells are offset from the inlet 22, thus permitting the intake air to flow into the carbureting chamber with minimum obstruction, this being desirable to enable the equipped motor (not shown) to operate with increased volumetric efficiency for reasons well known to those familiar with the art. Liquid in the float bowl flows into well 42 through port 45 and passageway 44, (see Fig. 14) this passageway having its outer end closed by plug 49. The liquid flow into the well may be regulated by turning head 48 of needle valve 46, threaded through the bowl cover as at 47, this needle serving to restrict the passage of fluid through port 45. Well 43 is similarly communicable with the bowl interior through passageway 44a and port 45a, the amount of liquid flowing from the bowl into well 43 being regulated by needle valve 46a threaded through the bowl cover and located in relation to valve 46 in the position clearly illustrated in Fig. 1. Thus it is seen that the wells are in separate communication with the bowl and

that separate regulation may be made of the liquid flow to each well.

Bores 40 and 41 are threaded within their lower portions to support tubes 50 and 51, the tubes having lower enlarged threaded portions 50a and 51a, respectively, for engagement with the bore threads. These tubes are drilled vertically at intervals, as at 52, and to terminally bear at their upper ends against the shoulders 53 at the ends of the bores. Extending upwardly from the intermediate speed well and co-axial with bore 40 are bores 55 and 56, progressively smaller in the order named, bore 55 being in communication with a horizontal bore 57. Extending above the high speed well and co-axial with bore 41, is a bore 58, opening into a horizontal bore 59, the latter being co-axial with bore 57. Plug 54a is screwed into the lower end of bore 41, and is spaced at its inner end from the threaded enlarged end 51a of tube 51 to form a liquid receiving space into which liquid flows from the bowl through passageway 44a. Integral with plug 54, which is screwed into bore 40 and spaced from end 50a of tube 50, is a tube 60 extending inwardly, in annularly spaced relation, through tube 50, through bore 55 and annularly spaced from the walls thereof, and terminally fitting snugly within bore 56, as illustrated at 61. Tube 60 is drilled at 62, as indicated in Fig. 6. A liquid level is maintained in the float bowl such that liquid may flow into the wells through lines 44 and 44a and rise to a level near the upper ends of bores 40 and 41, this level being substantially that illustrated by line L-L of Fig. 3. It is evident that in the intermediate speed well, liquid at height L-L will be contained within tube 60, between that tube and tube 50, and between the latter tube and the bore wall 40, communication being established between the bore wall and the tube interiors by means of apertures 52 in tube 50 and aperture 62 in tube 60. Similarly, liquid in well 43 may rise to height L-L within tube 51 and between that tube and the bore wall 41.

As indicated in Fig. 6 an atmospheric inlet passage 63 opens into the intermediate speed well at the uppermost portion of bore 40 adjacent shoulder 53. Screwed into the end of passage 63 is an apertured plug 64 having an air passageway made up of a diametrically extending portion 64a and an axial portion 64b, the latter being a comparatively restricted passage of predetermined size for controlling the amount of air admitted to the well through passage 63. A similar atmospheric inlet 66 extends into the high speed well, the flow of air into this well being regulated by plug 68 having a restricted passage similar to passage 64b in plug 64. When it is desired to admit air to either well in different amount from that obtainable through a plug having a certain sized air passage, that plug may be replaced by another having a passage of such size as to permit the desired flow of air therethrough.

Mounted above and in communication with the intermediate speed well is an auxiliary or idling speed control device, generally indicated at 70. Embodied in the idling speed control is a bore 71 in communication with the bore of tube 60 and with passageway 56 leading from the intermediate speed well, and a relatively small bore or jet 72, extending between bore 71 and the carbureting chamber 32. Bore 71 is in communication with the atmosphere through apertured plug 73, the amount of air flowing from the atmosphere through bore 74 into bore 71

being regulated by means of screw 75, as clearly illustrated in Fig. 3. In the event the pressure in the carbureting chamber drops below atmospheric, it is evident that through jet 72, suction is exerted on the intermediate speed well causing liquid therein to rise in tube 60 and through passageway or bore 56 into bore 71, and also causing atmospheric air to be drawn into the latter bore through passageway 74 in plug 73, 5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360

10 the mixture of fuel and air being drawn from bore 71 through the jet 72 into the carbureting chamber 32. For a constant suction pressure in chamber 32 the amount of fuel drawn through the jet from the intermediate speed well may be controlled by the idling speed air adjustment screw 75, as it is evident that as more air is admitted to bore 71 through passage 74, the less effective becomes the suction tending to draw feed liquid upward in passage 56. The discharge of fuel through tube 60, as described, may be accompanied by a slight lowering of the liquid level in the well between tubes 50 and 60 and between tube 50 and the bore wall 40.

Extending horizontally and diametrically across the carburetor air inlet 22 is a removable tube 76, termed the high speed spray tube for reasons that will later be made apparent, this tube extending within and snugly fitting in body bores 59 and 76a, at opposite sides of the inlet, as clearly illustrated in Fig. 8. Tube 76 is releasably held in position by means of set screw 77, extending through bore 77b and threaded into tube 76 at 77a. The tube is seen to have relatively large and relatively small co-axial bores 76b and 78a, respectively. Extending within and having a press fit in the smaller bore 78a, is an intermediate speed spray tube 78 spaced from bore wall 76b as at 79. Tube 78 extends beyond the intake end of the high speed spray tube and fits snugly in bore 57, previously described, thus establishing communication between the intermediate speed well and the interior of the intermediate speed spray tube. Tube 76 has nozzles or jets 80, increasing in size toward the open end of the tube and extending horizontally on opposite sides of the tube, substantially across one half of the inlet, these jets establishing communication between space 79 and the inlet 22. Jets 80a, similarly formed, extend through the high and intermediate speed tubes along their engaged portions and in line with jets 80, and substantially across the other half of the inlet, thus forming openings from the interior of tube 78 into the inlet 22. The spray tubes are purposely constructed and mounted in the described unitary manner to facilitate their removal from the carburetor body. Thus, should it be necessary to remove the tubes for cleaning or for replacement with a similar pair of spray tubes having different sized 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360

60 Jets, it is but necessary to remove set screw 77 and to pull the tube assembly outward through bore 76a.

It is evident that suction exerted on the intermediate speed well through jets 80a results in liquid being drawn upward from between tubes 50 and 60 into bore 55, then into bore 57 and tube 78, and outward into the air inlet through jet 80a. During the discharge of fuel from the intermediate speed well, the liquid outside tube 60 is depressed from level L-L, and apertures or ports 52 are successively uncovered, thus permitting air to flow from passageway 63 into the space above the liquid level between tube 50 and wall 40, and thence through the uncovered apertures 52 to be mixed with liquid being drawn upward

within tube 50. The amount of air admitted to the intermediate speed well and therefore the amount of suction tending to draw liquid from that well through jets 80a, is dependent upon the size of passage 64b in plug 64, previously described. When discharging under full intermediate speed operation, the liquid in the intermediate speed well preferably is completely depressed and the entire feed is drawn through passageway 44 leading from the float bowl. It is seen that the lowermost apertures, 52a, in tube 50 are somewhat larger than apertures 52, for the reason that when the liquid has been depressed to a low level in the well, it is desirable to discharge the last portion at a high rate before taking suction direct from the bowl through passage 44.

Liquid is discharged from the high speed well into inlet 22 in a manner generally similar to that described for the intermediate speed well. Due to suction through jets 80, the liquid rises within tube 51 into bore 58, then flows into horizontal bore 59 and the space 79 between tubes 76 and 78, and thence into the air inlet 22 through jets 80. Air, in regulated amount, is admitted to the high speed well through plug 68 and is mixed with fuel within tube 51 in amount according to the depression of liquid level in the well and therefore the number of apertures 52 uncovered by the depressed liquid. It is of particular advantage in the operation of the idling speed jet and the intermediate and high speed spray tube, that air and fuel are thoroughly mixed in the well before the mixture is discharged at high velocity and in mist-like form into the carbureting chamber 32.

Mounted centrally and longitudinally in the inlet 22 is a partition plate 81 which, for purposes of economic manufacture, may be formed integrally with the sides of the inlet and which is drilled at 81a to receive tube 76, the partition projecting slightly above the tube as at 81b. Thus it is seen that the partition divides the inlet into two passageways, one, 22a, for directing a portion of the inlet air past high speed jets 80, and the other, 22b, for directing air past the intermediate speed jet 80a. As clearly illustrated in Fig. 3 the valve is spaced in close proximity to the partition and outer tube 76, as at S, this space being sufficient to permit the flow of air, in certain instances which will later be described, from the inlet passageway 22a through space S and into the upper portion of passageway 22b.

I will now describe generally the operation of the carburetor, assuming that fuel is to be supplied to the motor operating first at idling speed, then at intermediate speed, and finally at high speed. The idling speed position of the throttle valve is indicated in Fig. 3. It is seen that suction from the engine manifold (not shown but applied to the flange 20c in the usual manner) through outlet 23, occurs through a comparatively small opening O, defined by the valve and the body 20. In this position of the valve, air is taken into the carbureting chamber through openings R and T, formed by valve slots 34 and 35, the openings being in communication with inlet air passageways 22a and 22b, respectively. Due to suction created in chamber 32 from the engine, liquid fuel and air are drawn into the chamber through the idling speed jet 72, previously described.

As the engine accelerates from an idling speed toward intermediate speed, resulting from the movement of the valve from the position of Fig.

3 in the direction of arrow D, the opening O is increased in size, thus causing increased suction from the engine tending to exhaust the carbureting chamber. During this operation opening R 5 becomes further closed and opening T further opened so that the combined area of the inlet openings remains substantially constant, the greater portion of air obviously being taken into the carbureting chamber through opening T. 10 The increased amounts of fuel and air taken into the carbureting chamber due to the increased suction therein, are in such proportions that the composition of combustible mixture discharged through opening O during the described variations within the idling speed limit is substantial- 15 ly constant.

During the operation of the idling speed jet, air flows past the intermediate and high speed jets through openings R and T, respectively, 20 with sufficient velocity that suction is exerted in these jets, due to the flow of intake air past them, causing liquid to be drawn from the well into the spray tubes. The suction is not sufficient, however, to draw fuel from the jets, but merely 25 to hold it in readiness for immediate discharge should the throttle suddenly be opened to full intermediate or high speed position. It is therefore evident that should the throttle be opened from the position of Fig. 3, to the intermediate 30 speed position of Fig. 4 or the high speed position of Fig. 5, fuel is held in the spray tubes ready for immediate discharge, so that "lagging" does not occur. As the valve plug is rotated to open position it has a sweeping motion over the 35 spray tubes and causes the jets to be successively brought into the direct path of the intake air, and to successively discharge fuel to the carbureting chamber.

In Fig. 4 it is seen that during operation of the 40 carburetor at full intermediate speed, the entire amount of air taken into the chamber 32 from inlet 22 flows through opening T, the greater portion flowing through passageway 22b past the intermediate speed jets 80a. A comparatively 45 small amount of air is, however, drawn from passage 22a through opening T by way of space S, this amount of air being just sufficient to cause liquid to be held in, but not discharge from the high speed tube. During intermediate speed 50 operation the greater portion of liquid taken into the carbureting chamber is from jets 80a, a comparatively small amount being discharged from the idling speed jet 72, due to the decrease in suction in chamber 32 as the valve is moved to open position, or as inlet T is increased and the amount of inlet air becomes greater. When the valve is moved to the wide open or high speed position of Fig. 5 the idling speed jet 72 55 becomes closed and fuel is sprayed into the chamber through both the intermediate and high speed jets. It is an advantage that in this position of the valve, the passage of air through inlet 22 is substantially unrestricted in its flow through the carburetor to the engine manifold.

As illustrated in Fig. 3 the intermediate and 60 high speed jets 80a and 80, become progressively of larger diameter in sequence in the direction of movement of the valve, this feature being of advantage in that as the opening T becomes greater as the valve moves to open position, the velocity of intake air may decrease and become less effective in drawing fuel from the spray tubes. However, by increasing the size of the jets, the discharge of fuel therefrom is facilitated, 65 and although the intake air velocity is decreased,

proper discharge from the spray tubes is maintained. Due to the extremely high velocity of discharge of fuel from the spray tube, it is evident that thorough admixture of this fuel with the intake air is effected before the combustible mixture leaves the carburetor. 80

The combined area of the jets in either spray tube preferably is substantially equal to the area of the valve opening in the feed liquid inlet to the well from which the tube is supplied. That is for example, the combined area of the intermediate speed jets 80a is substantially equal to the effective opening of port 46. The sizes of the jet openings may be determined by drilling the first intermediate speed jet J to deliver fuel in desired amount when the throttle is near the start of its intermediate speed path and when the entire discharge from the intermediate speed tube is occurring substantially through jet J, and to progressively increase the size of the remaining jets 80a, having their total area equal that of the effective area of port 46. 90

In Fig. 15 I have illustrated an embodiment of the invention, generally similar to the hereinabove described carburetor, with the exception that the body has certain structural characteristics that enable the carbureting chamber to be adjusted to inverted position, or in other words the relative positions of the inlet 22 and outlet 23 to be reversed. It is evident, furthermore, that the carburetor outlet may be adjusted in any intermediate or side position that might be desired for connection with a side draft manifold. In the preferred embodiment, the carburetor body is seen to contain two sections, one 20a, generally containing a float bowl 21 and intermediate and high speed wells 42 and 43, and a section 20b containing carbureting chamber 32, inlet 22 and outlet 23, the latter section being joined to section 20a as at 85. In order to convert the type of carburetor illustrated in Fig. 3 to that of Fig. 15, it is but necessary to divide the carburetor body, as illustrated, along the line 16-16 and to alter the position of parts of the idling speed control according to the changes made in body structure, to enable this control to operate at various adjusted positions of body section 20b. Spray tube 76 is mounted in a manner similar to that previously described, extending through the inlet 22 and snugly fitting the wall of bore 59 in section 20a. By virtue of the snug fit of the spray tube in bore 59, the tube may be used as means of support for body section 20b relative to section 20a, however, I prefer to join the body sections securely by means of screws 87 extending through flange portion 89 of body section 20a. It is evident that section 20b may be rotatably adjusted about spray tube 76 as an axis, that is, it may be rotated to the upright position 115 of the previously described carburetor type (as shown in dotted lines in Fig. 15) or may be inverted as shown in Fig. 15, or may be adjusted in any intermediate position. 120

In adapting the idling speed device to this particular form of carburetor body, a circular groove 86, concentric with the spray tube 76, is formed in the surface 85a of body section 20a, communication between this groove and bore 56, extending above the intermediate speed well, being accomplished by means of passageway 71a. The idling speed air adjustment 70a is mounted in vertical position and threaded into the body at 88, in the end of bore 56. Communication between circular groove 86 and the interior of the carburetor 130

- ing chamber is established by means of the idling speed jet bore 72a, formed in body section 20b and adapted to register with the circular groove in all adjusted positions of section 20b. With 5 the chamber 32 in inverted position, the carburetor operates as a down draft type, advantages of which have been set forth hereinabove. Although numerous advantages of the invention will be apparent from the foregoing description, certain salient features are emphasized at this point as being of special importance. The feed liquid wells have compensatory characteristics in that by their use, the feed is available for instantaneous delivery to the spray tubes 15 when rapid acceleration of the motor is desired, and that the amount of liquid held in the wells is sufficient to feed the jets until delivery to the tubes is made direct from the liquid inlets feeding the wells from the bowl. With the carburetor suitably adjusted, proper performance 20 may be had at varied altitudes. The adjustment features are such that when the carburetor operates at high altitude and the amount of air drawn through the carburetor is reduced, the 25 discharge of fuel into the carburetor chamber is automatically reduced and the effects of increased altitude compensated. The effects of temperature changes tending to alter the condition of the air are similarly compensated. 30 The carburetor is extremely reliable in operation, due to the absence of moving parts likely to afford difficulty in maintaining proper adjustment. It is evident that as the throttle valve is opened or closed the composition of the combustible mixture discharged from the carburetor 35 is controlled entirely by the velocity and suction of the air acting upon apertures of fixed sizes. As hereinbefore set forth in detail, the motor is able to operate with added efficiency due to the 40 large area of the restricted part of the air passage into the carburetor when the throttle is in open position, the use of the large air passage being made possible because the spray tubes are able to operate efficiently at extremely low suction. Because of the preliminary mixing of air 45 and fuel in the compensating wells, and due to the discharge at extremely high velocity of this mixture through the spray tubes, the fuel is broken up into a fine mist and thoroughly mixed 50 with air before leaving the carburetor. Although the carburetor in any single adjustment is adapted to perform efficiently within a wide range of operating conditions, this range of operability may be further increased by numerous 55 means of adjustment previously described.
- It will be understood the drawings and description are to be considered merely as illustrative of and not restrictive on the broader claims appended hereto, for various changes in 60 design, structure and arrangement may be made without departing from the spirit and scope of said claims.
- I claim:
1. In a carburetor, a spray tube assembly embodying an outer tube having a closed end and a pair of co-axial bores, the smaller bore extending from said closed end to an intermediate portion of the tube and the larger bore extending from said intermediate portion to the open 65 end of the tube, and an inner tube of outside diameter substantially equal to the diameter of said smaller bore, an end of the inner tube having a tight fit in said smaller bore and extending within and spaced from the larger bore wall to project beyond the open end of the outer tube, 70 the outer tube having a jet opening through the wall of said larger bore, and both tubes having co-axial jet openings through their engaged portions. 80
  2. In a carburetor for a motor, a body having an air passage and a valve chamber in said passage, a pair of feed liquid wells in the body and offset from said passage, a pair of spray tubes, the first tube extending into said air passage and in communication with one well, the second tube being in communication with the other well and extending within said first tube and spaced therefrom throughout a portion of its extent, said tubes being drilled to permit the flow of fuel from the one well into said chamber through the outer tube and from the other well through the inner tube, and a valve plug rotative in said chamber and provided with a passage, said valve being adapted to regulate the flow of air past 85 said tubes. 90
  3. In a carburetor for a motor, a body having an air passage and a valve chamber in said passage, an intermediate and a high speed feed liquid well in the body, said wells being offset from said passage, a high speed spray tube in communication with the high speed well and extending across said passage normal to the flow of intake air, an intermediate speed spray tube in communication with said intermediate speed well and extending within the other tube and spaced therefrom throughout a portion of its extent between the inlet end of the high speed tube and a point intermediate the walls of the carburetor air passage, said tubes being drilled to separately discharge 100 fuel into said chamber, an idling speed jet fed from the intermediate speed well and adapted to discharge into said chamber, and a cylindrical valve plug in said chamber and adapted through its successive movements to cause successive discharges of fuel from the idling speed, intermediate speed and high speed jets in the order named. 105
  4. In a carburetor, a body having an air inlet and outlet and a valve chamber between the inlet and outlet, an outer spray tube extending across said inlet and having a plurality of high speed jets adapted to discharge into one half of the inlet, an inner spray tube within the outer tube and having a plurality of intermediate speed jets extending through the outer tube and adapted to discharge into the other half of said inlet, a partition plate disposed centrally and longitudinally in the inlet and in engagement with said outer tube between the inner tube and outer tube jets, and a cylindrical ported valve plug having a passage and mounted for rotatory movement within the chamber and in close proximity to said outer tube and plate, said plug in one position having its passage in registration with said inlet and outlet and allowing equal amounts of air to flow past the high speed and intermediate speed jets, and in its intermediate positions having its passage partly closed to said inlet to allow intake air to flow in greater amount past the intermediate speed jet than past the high speed jet. 110
  5. In a carburetor, a body having a single air passage and an air inlet and outlet, a valve chamber between said inlet and outlet, a single Venturi throat at the inlet end of said valve chamber, a spray tube extending across said Venturi throat, and a cylindrical valve plug mounted for rotatory movement in said chamber and having a cylindrical passage extending at right angles to the axis of said plug, the passage being adapted to 115 register with said Venturi throat and the outlet 120

- when the valve plug is in open position, the plug in its closed position having a discharge opening between the passage and said outlet and a pair of suction openings between the passage and said 5 Venturi throat, said valve plug being adapted to move toward open position so that said outlet opening increases in size while one of said inlet openings increases and the other decreases in size.
6. In a carburetor, a sectional body, a first section containing a float bowl, a second section containing a carbureting chamber, said second section being connected to the first section so as to be rotatively adjustable with relation thereto, and a spray tube for delivering fuel from said bowl to 10 said chamber, said second section being rotatable about the spray tube.
7. In a carburetor, a sectional carburetor body, a first section containing a float bowl, an intermediate and a high speed well in communication 15 with said bowl, a flanged end portion, a bore in said end portion and in communication with said wells, an annular groove in the end portion and concentric with said bore, an idling speed jet feed passageway extending between the intermediate speed well and said groove; and 20 a second section containing an air inlet and outlet and a carbureting chamber between the inlet and outlet, a spray tube extending across the inlet and projecting into and engaged in said bore, said second section being joined to the first section at its flanged end portion and rotatable with relation thereto about said tube as an axis, and an idling speed jet bore in the second section 25 opening at its one end into the carbureting chamber and at its other end into said annular groove and adapted to register with said groove as the body sections are rotated relative to one another.
8. In a carburetor, a body having an air passage, a spray tube assembly extending across 30 said passage and comprising a pair of concentric tubes having a fluid passage therebetween, means for supplying fuel to the spray tubes, said tubes being apertured so that fuel is delivered to said 35 passage respectively from the inner and outer tubes at separate portions of said passage, a partition extending longitudinally in said passage between said separate portions thereof, and a valve in said passage adapted to permit the flow 40 of air successively through said separate portions of the air passage as the valve is moved from closed toward open position.
9. In a carburetor having a fuel and air mixing passage, a partition extending longitudinally 45 within said passage, a throttle valve for regulating the flow of air therein, said valve in moving from closed toward open position being adapted to permit a greater flow of air through 50 said passage at one side of said partition than at the other side, spray tube means extending within said passage transversely to the flow of air therethrough and adapted to discharge fuel, under control of said valve at opposite sides of 55 said partition and means for supplying fuel to said spray tube means.
10. In a carburetor having a fuel and air mixing passage, a partition extending longitudinally within said passage, a throttle valve for regulating the flow of air therein, said valve in moving 60 from closed toward open position being adapted to permit a greater flow of air through said passage at one side of said partition than at the other side, a spray tube extending transversely of 65 said passage from the side wall thereof and adapted to discharge fuel at one side of said partition
- under control of the valve, and means for supplying fuel to said spray tube.
11. In a carburetor for a motor, a body having an air passage, a partition in the passage, a valve at one end of the partition, a constant level supply bowl, a single Venturi throat in said passage, a pair of feed liquid wells in said body and offset from said passage, the wells being in communication with the bowl, a pair of fuel sprays both discharging into said Venturi throat at opposite sides of the partition, the first spray being in communication with one of the wells, the second in communication with the other well, a valve movable transversely of the plane of the partition and operable to cause the flow of air past one side of the partition before any substantial air flow occurs past the other side, so that one spray is caused to discharge fuel before the other. 80
12. In a carburetor for a motor, a body having an air passage, and a valve in said passage, a constant level supply bowl, a single Venturi throat in said passage, a pair of feed liquid wells in said body and offset from the air passage, the wells being in communication with the bowl, an idling jet fed from one of the wells, an intermediate 85 speed and a high speed spray passage within said single venturi at points intermediate its ends, the intermediate speed spray passage being in communication with one of the wells and the high speed spray passage in communication with the other 90 well, one of said spray passages extending within said partition, and a valve within said chamber for controlling the passage of air through the chamber and adapted through its successive movements to cause successive discharges of fuel 100 from the idling speed jet and intermediate speed, and high speed sprays in the order named, said valve operating to cause the flow of air past one side of said partition in greater amounts than 105 past the other side as the valve moves from closed 110 to open position.
13. In a carburetor, a body having an air passage and a valve in said passage, a fuel supply chamber, a single Venturi throat in said passage, a pair of fuel wells in said body and offset from the air passage, said wells being in communication with the fuel chamber, a partition extending longitudinally within said venturi, a pair of fuel 115 spray passages communicating with said wells and extending transversely within said air passage, one of the passages extending within said partition, said fuel passages discharging at opposite sides of the partition, and a throttle valve in said passage operable in moving from closed to 120 open position to cause a substantially greater flow of air past one side of said partition than past the other side. 125
14. In a carburetor, a body having an air passage and a valve in said passage, a single Venturi throat in said passage, a pair of sprays, both discharging into said Venturi throat, the first discharging to one portion of the Venturi throat, the second discharging to another portion of the Venturi throat, means for supplying fuel to said sprays, a partition between said portions and extending below points at which fuel is discharged from said sprays, and a rotatable valve in said passage adapted through successive movements to permit the flow of inlet air past one spray and past one side of the partition before any substantial amount of inlet air flows past the other spray and past the other side of the partition, said valve being movable in a direction transversely of the 130 plane of said partition. 135
15. In a carburetor, a body having an air passage and a valve in said passage, a single Venturi throat in said passage, a pair of sprays, both discharging into said Venturi throat, the first discharging to one portion of the Venturi throat, the second discharging to another portion of the Venturi throat, means for supplying fuel to said sprays, a partition between said portions and extending below points at which fuel is discharged from said sprays, and a rotatable valve in said passage adapted through successive movements to permit the flow of inlet air past one spray and past one side of the partition before any substantial amount of inlet air flows past the other spray and past the other side of the partition, said valve being movable in a direction transversely of the plane of said partition. 140
16. In a carburetor, a body having an air passage and a valve in said passage, a single Venturi throat in said passage, a pair of sprays, both discharging into said Venturi throat, the first discharging to one portion of the Venturi throat, the second discharging to another portion of the Venturi throat, means for supplying fuel to said sprays, a partition between said portions and extending below points at which fuel is discharged from said sprays, and a rotatable valve in said passage adapted through successive movements to permit the flow of inlet air past one spray and past one side of the partition before any substantial amount of inlet air flows past the other spray and past the other side of the partition, said valve being movable in a direction transversely of the plane of said partition. 145
